(57) CLAIM

The ornamental design for an educational plush toy, as shown and described.

DESCRIPTION

FIG. 1 is a front perspective view of an educational plush toy.

FIG. 2 is a back perspective view thereof.

FIG. 3 is a front elevation view thereof.

FIG. 4 is a rear elevation view thereof.

FIG. 5 is a left-side elevation view thereof.

FIG. 6 is a right-side elevation view thereof

FIG. 7 is a top plan view thereof; and,

FIG. 8 is a bottom plan view thereof.

The broken lines in the drawings illustrate portions of the educational plush toy that form no part of the claimed design.
